Specification for Design.

Patented July 30, 1912.

Application filed January 18, 1912. Serial No. 672,002. Term of patent 7 years.

To all whom it may concern:

Be it known that I, ALBERT EDWARD LOVATT, a subject of the King of England, and a resident of Heanor, Derbyshire, England, have invented a new, original, and ornamental Design for Water-Bottles, of which the following is a specification.

In the drawings, Figure 1 is a plan view of a water bottle embodying my design, and Fig. 2 is a side elevation thereof.

I claim:—

The ornamental design for a water bottle as shown.

In testimony whereof I have affixed my signature in the presence of two witnesses.

ALBERT EDWARD LOVATT.

Witnesses:

ARTHUR FRANK EALEY,
CHARLES JOSHUA WILSHIRE.
